(57) **CLAIM**

The ornamental design for a security fence panel, as shown and described.

DESCRIPTION

FIG. 1 is a front perspective view of a security fence panel with broken lines indicating a call-out location for the detail view of FIG. 7;

FIG. 2 is a front elevation view of the security fence panel shown in FIG. 1;

FIG. 3 is a rear elevation view of the security fence panel shown in FIG. 1;

FIG. 4 is a left side elevation view of the security fence panel shown in FIG. 1;

FIG. 5 is a right side elevation view of the security fence panel shown in FIG. 1;

FIG. 6 is a top plan view of the security fence panel shown in FIG. 1; and,

FIG. 7 is a detail view of the security fence panel shown in FIG. 1 with a broken line border matching the broken line call-out location of FIG. 1.

The broken lines in FIGS. 1-5 depicting portions of the security fence panel and the dash-dot lines indicating a boundary of the claimed design form no part of the claimed design.
